CRUET

Peter L. Schweizer, Liberty Center, Ohio, assignor to
Owens-Illinois, Inc., Toledo, Ohio

Filed Jan. 15, 1973, Ser. No. 323,888

Term of patent 14 years

Int. Cl. D7—06; D9—01

U.S. Cl. D7—52

FIG. 1

FIG. 2

FIG. 3

FIG. 4

FIG. 1 is a front elevational view of a cruet showing my new design;

FIG. 2 is a side elevational view thereof;

FIG. 3 is a top plan view thereof; and

FIG. 4 is a sectional view, at an enlarged scale, taken on line 4—4 of FIG. 1.

The back is the same in appearance as the front which is shown in FIG. 1, and the side opposite that seen in FIG. 2 is the same in appearance as the side shown.

I claim:

The ornamental design for a cruet, substantially as shown and described.
